FLOATABLE SLIP-RESISTANT SHOE

Edgar B. Cartmell, Bethany, Conn., assignor to United States Rubber Company, New York, N. Y., a corporation of New Jersey

Application July 30, 1954, Serial No. 446,735

2 Claims. (Cl. 36—2.5)

This invention relates to a self floating shoe having a non-water absorbent, cellular, flexible, relatively soft and resilient slip resistant plastic sole of sufficiently low specific gravity to float the shoe in water. 15

The shoe embodying this invention is particularly useful on boats to prevent the loss of the shoe by sinking into the water, in the event that it falls, or is washed overboard into the water, which frequently happens on small boats where the boatsman removes his shoes and leaves them on the deck of the boat. The shoe is also useful on wet decks to prevent the wearer from slipping.

The shoes are caused to float in the water by making the soles of sufficiently low specific gravity and of sufficient volume to displace sufficient water to float the entire shoe, and the shoes are made slip-resistant by slitting the tread surface of the soles. To provide the shoes with the floatable characteristic, the soles are made of closed cell, flexible soft resilient plastic material, which is non-water absorbent. Such material has good wear resistant qualities, and has the further advantage of being comfortable to the foot by virtue of its lightness and soft 35 flexible resilient qualities, which is further increased by the slitting effect of the tread surface.

The closed cell non-water absorbent material has improved slip resistant qualities as compared to non-cellular rubbery materials heretofore used in soles, and when slitted its slip resistant qualities are superior to such non-cellular rubbery material.

The foregoing and other objects and advantages of this invention are further described in reference to the accompanying drawings, in which

Fig. 1 is a perspective view of the bottom and side of the shoe and showing the slitted tread surface of the outsole;

Fig. 2 is a transverse section through the shoe on line 2—2 of Fig. 1; and

Fig. 3 is an enlarged section of the tread surface of the outsole enclosed within the square formed by the dot and dash lines in Fig. 1.

Referring to the drawings, the shoe embodying this invention comprises an outsole 11, which is secured to an upper 12 by any conventional means. As illustrated herein, the upper 12 may be made of canvas and lasted over an insole 13, to which the usual filler material 14 is applied, and the outsole 11 is bonded to the bottom of such upper with a suitable cement in the conventional manner.

The outsole 11 and the heel piece 15 is made of a plastic material containing a blowing agent, which is molded and blown to form closed cell cellular material. The sole 11 and heel piece 15 may be molded in one piece, or the tread parts may be cut from molded sheet material and cemented together.

After the outsole 11 has been formed and before it is applied to the shoe, the tread surface thereof is provided with transverse saw-tooth slits 16. Such slits are made by cuts, or incisions made into the rubber to a depth of about one-eighth of an inch and spaced from

each other in the heel to toe direction a distance of about $\frac{3}{32}$ of an inch. The incisions may be made into the tread surface as described in United States Patent No. 2,284,307 to Paul A. Sperry, granted May 26, 1942. The walls of the slits remain closed when the sole is not stressed and prevent the entry of dirt or foreign matter, but such slits open up under the pressure of the foot on a slippery wet boat deck. The exposed corners of the open slits wipes the wet surface dry as a squeegee and prevents slippage. 10 The outsole 11 may be made from suitable plastic compositions containing rubbery materials, and blowing and curing agents. The following composition is given as an example:

Composition

Ingredients	lbs.	ozs.
GR-S (Butadiene-Styrene rubbery Copolymer—Smoked Sheet)	126	12
“Cumar Resin R-16” (Cumarone-Indene resin)	25	0
Titanium oxide	14	8
“Hi-Sil” (Precipitated hydrated Silica)	10	0
Zinc oxide	45	0
Stearic acid	14	6
“Altax” (Benzothiazyl disulphide)	7	4
Phenyl ortho-tolyl guanidine	1	13
“FW-100 Solka Flock” (Highly purified cellulosic flock)	13	9
“Suprex” Clay (Clay)	110	0
“Circo Oil” (Light hydrocarbon oil)	36	0
High Styrene-Low Butadiene Resinous Copolymer	27	8
Monex (Tetramethyl-Thiuram-Monosulphide)	9	11
Cellogen (p,p'-oxybis [benzene sulfonyl hydrazide])	10	8
Sulphur	3	8
	447	15

In processing the above composition all of the ingredients excepting the Cellogen and sulphur are mixed on a Banbury machine. The Banbury mix is then put on a calender and mixed with the Cellogen and sulphur. The stock is calendered to the required thickness to make a sole of the desired thickness after expansion. For example to make a sole having a thickness of .750 inch, the stock is calendered to a thickness of .52 inch and placed in a mold having a depth equal to the thickness of the stock, which is cut to the dimensions required to fill the mold. After being placed in the mold, the stock is cured in the usual vulcanizing press under a pressure of about 1000 p. s. i. at a temperature of about 290° F. for 10 to 12 minutes.

The molds are then opened, and the slabs of stock are cooled to room temperature. The slabs are then heated for about 6 hours at 220° F. so as to stabilize the expanded slabs. Then the slabs are allowed to cool at room temperature, and sanded to the gauge required for the outsoles which are cut to the desired shape and size to be applied to the shoe upper 12.

Such material is provided with closed blown cells, which is non-water absorbent, and soft and resilient. Such material has the resistance required for sole material, although it is cellular and slitted. Depending upon the quantity of blowing agent the material may be provided with a specific gravity of from .30 to .90 which is sufficiently low to float a canvas shoe when a sole of one-half inch or greater in thickness is applied to the shoe.

While the preferred form of this invention has been described herein more or less in detail, it is to be understood that changes may be made without departing from the spirit of this invention, and it is intended to cover such changes in the appended claims.

Having thus described my invention, what I claim and desire to protect by Letters Patent is:

1. A shoe comprising a woven textile fabric upper and a sole having as a whole a specific gravity less than water, said sole being composed of flexible, cellular, non-water absorbent plastic material having a closed gas filled cell structure and a specific gravity of from .30 to .90,

3

and said sole having a thickness of at least one-half inch and a tread surface provided with closely spaced transversely extending slits.

2. A shoe comprising a woven textile fabric upper and a sole having as a whole a specific gravity less than water and a thickness of at least one-half inch, said sole being composed of flexible, cellular, non-water absorbent plastic material having a closed gas filled cell structure and a specific gravity of from .30 to .90, and said sole having a slip-resistant tread surface provided with transversely 10 extending slits spaced from each other in the heel to toe

direction about $\frac{3}{32}$ of an inch and cut to a depth of about $\frac{1}{6}$ of an inch.
